UNITED STATES PATENT OFFICE.

JOHN JOSEPH DUKET, OF TOLEDO, OHIO.

OIL-BURNER.

1,280,425.

specification of Letters Patent. Patented Oct. 1, 1918.

Application filed March 4, 1918. Serial No. 220,186.

To all whom it may concern:

Be it known that I, JOHN JOSEPH DUKET, a citizen of the United States, residing at Toledo, in the county of Lucas and State of Ohio, have invented certain new and useful Improvements in Oil-Burners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a generator and burner for utilizing heavy fuel oils for heating and for cooking and its object is to provide a device which shall be simple, safe and efficient and, more particularly, to provide a gas generator with an outlet which shall be self cleaning and proof against the accumulation of adhering carbon and sediment; to provide such device with a generator which may be readily cleaned and which may be easily removed or installed; to provide an arrangement of the parts whereby a single generator and air-mixing chamber are adapted to supply gas mixed with air to either or any or all of a plurality of burners, each of such burners being controlled by means of a separate valve; to provide an improved arrangement of parts whereby each of the burners of my device may be independently adjusted to the most efficient location for use in the ordinary cooking or heating stove; to furnish a construction by means of which should any unconverted oil escape through the generator it will flow into the air-inlet pipe and thence out into a safe receptacle, while, at the same time, should any gas escape through this drain the gas will mingle with the inflowing air and will be carried to the air-mixing chamber and thence to the burner or burners.

The invention is fully described in the following specification, and while it is capable of embodiment in numerous forms, a preferred embodiment thereof is illustrated in the accompanying drawings, in which—
0 Figure 1 is a top plan-view of my device; Fig. 2, a front elevation of the same; Fig. 3, a transverse, sectional elevation of a portion of the same taken on line $\alpha-\alpha$, Figs. 1 and 2; Fig. 4, a central longitudinal sectional elevation of the generator hereinafter referred to, together with its controlling

valves and supports; Fig. 5, a central horizontal sectional plan-view of the valve piece 30 hereinafter referred to, on an enlarged scale; Fig. 6, a central vertical sectional elevation of one of the valves hereinafter referred to; Fig. 7, a central longitudinal sectional plan-view of the discharge end of the generator hereinafter referred to, on an enlarged scale, and Fig. 8, a side-view of the valve-stem supporting bracket 28 hereinafter referred to, detached.

Like letters and numerals of reference indicate like parts throughout the drawings.

In the drawings, 1 is a supply pipe and duct leading from a pressure tank,—not shown,—to the inlet of a generator-tube 2 through an oil supply valve 3. 4 is a valve-stem having a handle 5. This valve-stem carries a valve 6 adapted to seat as at 6^a to control the flow of gas or oil from the generator-tube. Projecting forwardly from the valved end of the generator is a needle-like portion 7 which extends into and through a sharp edged orifice 8 which leads from the surrounding chamber 9. This chamber is designed to catch particles of carbon or sediment which might clog the orifice 8. The needle 7 is longitudinally grooved as an additional means for preventing the closing of the orifice 8. Around the stem 4 in the generator-tube is wound spirally a wire 10 for breaking up the oil and for retarding its flow and prolonging its exposure to the heat of the tube and coil 90 in a subdivided condition. The aperture 3 leads into an air-supply pipe 11 which opens into a mixing chamber 12 leading into a valve-chamber, the casing of which is designated at 13. (See Figs. 1 and 3.) In this valve-chamber, 14, are located four valved outlets, viz., 15, 16, 17 and 18. Valve 15 controls a passage 19 connected as at 20, with a burner 21 for heating the generator and located immediately beneath and parallel with the generator-tube 2. Valve 16 controls a passage through the swinging arm 22 leading to the burner 23. Valve 17 controls a passage through swinging arm 24 leading to the burner 25. Valve 18 controls a passage 26 leading to the adjustable oven burner 27. These four valves have stems 15^a, 16^a, 17^a and 18^a, all of which,—together with the other valve-stems mentioned herein,—terminate at one end of the device close together and which are arranged for convenient access. The projecting ends of

these four valve-stems are supported and held in proper alinement by the bracket member 28 (see Fig. 8,) having downwardly projecting arms provided with apertures 15^b, 16^b, 17^b and 18^b, which apertures receive and support the corresponding valve-stem ends. The piece 28 has at one edge a jaw 29 which receives one end of the generator-tube as well as the piece 30 represented in plan view in Fig. 5. The upper jaw member of the jaw 29 carries a set screw 29^a and the lower jaw member has a socket 29^b which receives a lug 30^a on the piece 30. The oil inlet-duct 1 controlled by valve 3, 15 (see Fig. 4), is in communication with the oil-inlet of the generator tube, and when the set screw 29^a is set up a tight joint is established between these two portions of the oil duct. In communication with the oil duct 20 1 in the piece 30 is an oil duct 31, controlled by a valve 32, which duct leads to and discharges into the oil-pan 33 provided to receive oil for preheating the generator. An extension 34 from the oil-pan passes through 25 and is secured in hole 35 in the piece 28 and supports in operative position the bracket member 28 and its connected parts.

Leading from the mixing chamber 12 is a down pipe 36 which at its lower end is connected with the air inlet pipe 11, the arrangement being such that in case there is an overflow of oil from the generator-tube into the air mixing pipe, it will flow down into the air-inlet pipe and thence into a suitable receptacle—not shown. In case unconsumed gas or vapor is carried into the down-pipe 36 it will mingle with the ascending air and pass into the mixing chamber.

The arms 22 and 24 which carry the burners 23 and 25 are swiveled at their inner ends, as at 22^a and 24^a upon the top of the valve casing 13. These arms are hollow and they provide passages which at their inner ends are in communication with their appropriate gas-outlets in the valve-chamber 14, as above described, and at their outer ends are in communication with the chambers of the burners 23 and 25. These burners are hollow rings, radially kerfed on their upper sides, and are swiveled at one side upon their respective arms, as illustrated in Figs. 1 and 3. This arrangement of the swinging arms and of the swinging burner-rings permits a wide adjustment of the burners in every direction horizontally, so that the burners may be placed to accommodate the stove-holes of any cooking stove or range with which my device may be associated.

The oven burner consists of an elongated hollow casting having a hollow lug which is pivoted upon the side of the valve casing 13 as clearly illustrated in Fig. 1. The chamber of the burner 27 is in communication with the gas chamber 14 through passage 26 controlled by the valve 18 as above point-

ed out. The oven burner 27 may be tilted to such position as will prove most efficient in relation to the front wall of the bake oven of an ordinary cook-stove and may be rigidly secured in such adjusted position by means of screw bolt 27^a which also serves as a pivot pin. 70

37—37 are stout bolts which are screwed into the under side of the device and which form vertically adjustable legs which support the burners and generating apparatus in horizontal position at such height as may be desired. 75

The operation of my device is as follows: To start the apparatus the valve 32 is opened 80 to supply a sufficient quantity of oil to the generator pan 33 which is supplied with a suitable wick. The oil is next ignited. When the generator-tube 2 which lies in the flame from the pan 33, becomes sufficiently 85 heated, the valve 5 is opened permitting the oil to flow into the generator-tube. In its slow passage through the tube in contact with the walls of the tube and the hot coiled wire the oil is vaporized and turned to a 90 gas which discharges through the valve 6 and the orifice 7, and mingles with the air supply. The mixture is conducted to the valve chamber 14 by the pipe 12 and is thence distributed through the several valves 95 heretofore referred to in the manner described. The oil in the pan 33 being consumed, the valve 32 is closed and the valve 15 is opened and gas is now supplied to the burner 21 which continues to supply a flame 100 to the generator-tube as long as the supply of gas is continued. It will be seen that the supply of fuel oil may be regulated as may be desired and that either or any or all of the burners may be used as may be desired. 105

Having described my invention, what I claim and desire to secure by Letters Patent, is—

1. In a device of the described character, a generator-tube having at one end an oil inlet and at its other end a gas outlet, a valve for the control of said outlet, said valve having a stem which extends through the tube, and a wire coiled around substantially the full length of said stem within the tube, 115 whereby the metal heating surface within the tube is augmented and whereby the oil is broken up and retarded in its flow through the generator-tube, and whereby the freeing of the tube from carbon is facilitated. 120

2. In a device of the described character, a generator-tube having an oil inlet at one end and having at its opposite end a gas outlet, said outlet including a sharp edged orifice, a longitudinally grooved elongated needle-like member which projects through and regulates but does not close the opening of said orifice, and a valve which controls said gas outlet. 125

3. In a device of the described character, 130

- a generator-tube having at one end an oil inlet and at its other end a gas outlet, said outlet comprising a port having a valve-seat, said port leading into a chambered extension 5 of the tube, there being a sharp edged orifice leading from such chamber, a valve which governs the inlet to the tube, a valve-stem which carries a valve in operative relation to said valve-seat, and a forwardly projecting needle-like member carried by the valve-stem and which projects through said orifice, combined with a wire coiled around substantially the full length of said stem within the tube.
- 15 4. In a device of the described character, a generating tube having a valve controlled oil inlet and a valve controlled gas outlet, an air supply pipe, a chambered member in communication with the gas outlet and the 20 air inlet, and a conduit for unconverted oil which conduit leads from such chamber into the air inlet pipe.
5. In a device of the described character, a generator-tube having at one end an oil 25 inlet and at its other end a valved gas outlet, an air-duct into which leads said outlet and which forms a mixing chamber, a plurality of burners operatively connected with said mixing chamber, one of which burners 30 heats said generator-tube, and between said mixing chamber and said generator burner an independent regulating valve.
6. In a device of the described character, a generator-tube having a valved oil inlet 35 and a valved gas outlet, a burner for heating said tube, an air-supply pipe, a plurality of other burners, a hollow member the chamber of which is connected with said gas outlet and with said air-supply and which 40 forms a mixing chamber and a valve-chamber, for each of said burners a conduit leading from the mixing chamber, for each of said conduits a valve in said chamber, and for each of said valves an elongated valve-stem for the independent control of said 45 several valves.
7. In a device of the described character, a generator-tube adapted at one end for operative connection with a suitable oil supply 50 and having at its other end a gas outlet, an
- air-supply pipe, a hollow member the chamber of which is connected with said gas outlet and with said air-supply pipe and which forms a mixing chamber and a valve chamber, a gas burner in operative relation to said 55 generator-tube, a plurality of other burners, for each of said burners a conduit leading from the mixing chamber, for each of said conduits a valve in said chamber, and means for the separate independent control of each 60 of said several valves.
8. In a device of the described character, a generator-tube having at one end an oil-supply inlet and having at its other end a gas outlet, an air-supply pipe, a hollow member 65 the chamber of which is connected with said gas outlet and with said air supply pipe and which forms a mixing chamber and a valve chamber, a gas burner, a horizontal hollow arm upon the outer end of which the 70 gas burner is adjustably swiveled, swiveled connections between the inner end of said arm and said chambered member, said burner being in communication through said arm with said chamber, in said chamber a 75 valve which controls the passage from the chamber to the burner, and means for the control of said valve.
9. In a device of the described character, a generator-tube having a valved oil inlet 80 and a valved gas outlet, a gas burner for heating said tube, a plurality of other burners, swiveled connections for the adjustment of said other burners, an air-supply pipe, a 85 hollow member the chamber of which is connected with said gas outlet and with said air supply and which forms a mixing chamber and a valve chamber, for each of said several burners a conduit leading from said chamber, for each of said conduits a valve in said 90 chamber, and for each of said valves a valve-stem for the independent control of said several valves.

In testimony whereof I affix my signature in presence of two witnesses.

JOHN JOSEPH DUKET.
